UNITED STATES PATENT OFFICE.

FRANK E. KENNEY, OF PORTLAND, OREGON, ASSIGNOR OF ONE-HALF TO DANIEL W. HOELBING AND ONE-SIXTEENTH TO ELLA HOELBING, BOTH OF PORTLAND, OREGON.

SUBMARINE PROJECTILE.

1,184,699.

Specification of Letters Patent.

Patented May 23, 1916.

Application filed August 31, 1915. Serial No. 48,358.

To all whom it may concern:

Be it known that I, FRANK E. KENNEY, a citizen of the United States, and resident of Portland, county of Multnomah, State of Oregon, have invented a new and useful Improvement in Submarine Projectiles, of which the following is a specification.

This invention relates to projectiles adapted to be shot from a gun of standard type. 10 In experimentations made by me, I have discovered that an auger-like projectile, if discharged in the water, will thread its way through the latter in a right line, while as is well known, any other type of projectile 15 will not penetrate the water to any depth.

Therefore, the object of my invention is to make use of this discovery, and to construct a submarine projectile, that is to say, a projectile which is to be discharged from 20 a gun mounted above the water and fired into the water, so that the projectile will keep on its course in a right line for some distance after it strikes the water. To this end my projectile is constructed as herein- 25 after described and illustrated in the accompanying drawings.

In the latter, Figure 1 is a longitudinal, vertical section of a gun, showing my submarine projectile in the position of being 30 shot therefrom, Fig. 2 is a larger sized detail of the right portion of Fig. 1, showing one member of the projectile in section; and, Fig. 3 is a diagrammatic view showing the manner in which the projectile is used.

35 A standard gun is represented by *a*, *b* is the barrel, and *c* are the riflings of the barrel.

The projectile which comprises my invention, consists of a cylindrical tube *d*, adapted 40 to closely fit the bore of the barrel *b*. Said tube is provided with a plurality of copper packing rings *e*, adapted to engage the riflings of the gun and thus cause a rotation of the projectile during its flight. In the 45 rear end of the tube *d* is a plug *f*, which forms the base of the projectile.

An elongated body *g* is provided on its forward end with a nose *h*, and a detonator head *i*, of usual construction. The interior construction of the body *g* is not detailed here-

in, as it forms no part of my invention, but it is to be understood that said body is of the explosive type, being adapted to be exploded when the detonator head *i* contacts with any solid body. On the rear end of 55 the body *g* is a projecting member *j* of square cross-section, which is adapted to fit loosely in a corresponding hole of the plug *f*.

Formed on the exterior of the body *g* is a spiral rib *m*, said rib being slightly smaller 60 in diameter than the inner diameter of the tube *d*. Furthermore, the rib *g* is spirally formed in the same hand as the riflings of the gun, so that when the latter is fixed, the rotation given to the projectile will cause 65 the body *g* to thread its way through the water, instead of the rib *m* acting as a resistance member.

The general action of the projectile in being discharged, is shown in Fig. 3. As soon 70 as the rotating projectile leaves the muzzle of the gun, *a*, the resistance of the air or water will retard the tubular body *d*, and the explosive member *g* of said projectile will continue on its flight. 75

The auger-like action of the projectile body *g* will cause it to thread its way through the water in a right line, and thus make it a highly efficient instrument of warfare, for use in combatting the attack of a 80 submarine vessel. Furthermore, it is to be understood that this projectile may be adapted for use by submarine boats, or torpedo boat destroyers. Under such circumstances, the projectile would assume the characteristics of a torpedo, and would be projected from a torpedo tube under water. 85

I claim:

1. A projectile consisting of a tubular body, provided with circumferential means 90 for fitting the tube to the bore of the gun from which the projectile is to be fired a plug closing the rear end of said tube, a cylindrical elongated body detachably affixed to said plug, and projecting axially 95 therefrom, said elongated body formed with a peripheral spiral rib, said tube extending over said spiral.

2. A projectile consisting of a tubular body, provided with circumferential means for 100

fitting the tube to the bore of the gun from which the projectile is to be fired, a plug closing the rear end of said tube, a cylindrical elongated body detachably affixed to said plug, and projecting axially therefrom, said elongated body formed with a peripheral spiral rib, said tube extending over said

spiral, the means by which the elongated body is detachably affixed to said plug being adapted to cause the two parts to rotate 10 with the same velocity while passing out of the muzzle of the gun.

FRANK E. KENNEY.
